SPRAY GUN

William P. Dalrymple, Rochester, N. Y., assignor
to American Brake Shoe Company, Wilming-
ton, Del., a corporation of Delaware

Application April 10, 1948, Serial No. 20,210

1 Claim. (Cl. 299—140)

1

This invention relates to spray guns of the type utilized for spraying surface coating materials, and particularly the invention relates to spray guns for spraying emulsions of materials such as asphalt.

While spray guns have heretofore been provided for spraying emulsions, such guns were what may be termed special guns which were designed and manufactured differently than most conventional spray guns. Such guns were therefore relatively expensive. It is therefore an important object of the present invention to enable emulsion spray guns to be made in a large measure from standard parts that are used in the more widely used paint spray guns, and a related object is to enable this to be done in a simple and expeditious manner.

Other objects are to enable the emulsion control valve in such a gun to be operated by the usual material-control valve actuating structure of a paint spray gun; to enable an emulsion nozzle structure to be put in place in a simple manner on a gun body of the construction used for paint spray guns; and to simplify manufacture, upkeep and cleaning of such guns.

Other and further objects of the present invention will be apparent from the following description and claim and are illustrated in the accompanying drawings which, by way of illustration, show a preferred embodiment and the principles thereof and what I now consider to be the best mode in which I have contemplated applying those principles. Other embodiments of the invention embodying the same or equivalent principles may be used and structural changes may be made as desired by those skilled in the art without departing from the present invention and the purview of the appended claim.

In the drawings:

Fig. 1 is a vertical sectional view taken through an emulsion spray gun embodying the features of the invention;

Fig. 2 is a front elevational view of the spray head as viewed from the right in Fig. 1; and

Fig. 3 is a vertical sectional view taken along the line 3—3 of Fig. 1.

For purposes of disclosure the invention has been illustrated in the drawings as embodied in a pistol-grip type of spray gun of the same general construction as the spray gun disclosed in my copending application Serial No. 734,819, filed March 14, 1947. This spray gun has a main body 10 with a downwardly extending handle 11 at what may be termed the rear end of this body. At the forward end of the body

2

10, an adapter fitting 12 is secured in place on the body 10 by means including a cap screw 13, and at the forward end of the fitting 12, a spray head 15 is secured in place by a threaded retaining collar 16. The emulsion material is conducted into the fitting 12 at the lower end thereof through a supply inlet pipe 17 that defines a large area material passage 17M within the fitting 12. At its upper end the passage 17M is in valve-controlled communication with a horizontal passage 18 formed in an internal nozzle member 20 that is threaded into the forward face of the fitting 12 so as to abut the forward face thereof, as will hereinafter be described in detail.

15 The flow of emulsion material through the nozzle 15 is controlled by a valve 28 which will hereinafter be described in detail, this valve being removably mounted on the forward end of a valve stem 29 that extends rearwardly and is adapted to be operated to open the valve 28 by a main control lever 30 in the manner described in the aforesaid copending application, and when the valve 28 is opened, the emulsion material is withdrawn or aspirated through the nozzle 15 by the passage of pressure air through the nozzle 15 as will hereinafter be described. Such pressure air is supplied through a passage 32 formed in the handle 11 as described in the aforesaid copending application, and a main valve 34 is arranged to control such air passage and is in turn controlled by the main control lever 30. The air which passes the main valve 34 passes into another passage 33 in the handle 11 and is discharged upwardly through an adjustable sleeve valve 35 and into a horizontal passage 36 that extends forwardly in the body 10 so as to open through a forward face 10F on the body 10 and into the fitting 12, as will be described.

As pointed out hereinbefore, the primary structural elements of the emulsion gun of the present invention are of the same form and structure used in producing spray guns for handling paint and like materials, and in this regard it will be noted that the main body 10 has a 40 mounting lug 38 projecting downwardly therefrom and at the forward end thereof so that the forward face of the lug 38 constitutes a downward continuation of the surface 10F. The lug 38 constitutes a part of the means for mounting the adapter fitting 12, and a horizontal bore 39 is formed therein in alignment with a valve operating sleeve 40 that is mounted within and extended through the sleeve valve 35 as described in the aforesaid copending application. The 45 sleeve 40 has an inturned flange 40F at its for-

ward end, and a spring 41 is disposed in the sleeve 40 for affording a yielding connection between the sleeve 40 and a valve stem element such as the stem 29, as set forth in such co-pending application.

The fitting 12 is provided with a rear surface 12R which is disposed against the front face 10F of the body 10, and at its upper end the fitting 12 has a flange 12T through which the securing screw 13 is extended into the body 10 above the passage 36. The fitting 12 has a mounting nipple 42 extended rearwardly through the opening 39 in the lug 38, and rearwardly of the lug 38 a fastening nut 43 is threaded onto the nipple 42. The nipple 42 has a bore 44 formed axially thereof through which the stem 29 slidably extends, and a packing recess is formed in the rear end of the nipple within which a packing 45 and a spring 46 are disposed, and the spring is compressed by a packing nut 47 threaded onto the rear end of the nipple 42. At its rear end the stem 29 has a head 29H formed thereon which is disposed within the sleeve 40 and is held against the flange 48F by the spring 41.

At its forward end the fitting 12 has an extension 12E that is concentric with the bore 44 and this extension 12E terminates in a forward face 12F that is parallel to the face 12R. A threaded bore 50 is formed rearwardly through the face 12F so as to be concentric with the bore 44, and this bore 50 opens into the upper end of the inlet passage 17M. The forward end of the threaded bore 50 is tapered as at 50T to afford a seat for a rearwardly tapered head 29H that is formed on the inner nozzle 20. The inner nozzle 20 is generally sleeve-like in form so that rearwardly of the head 29T, the nozzle 20 has a threaded nipple 28N which is threaded rearwardly into the bore 50 so as to seat complementary tapered surfaces of the head 29T in the tapered seat 50T, and when this relation is reached, the rear end of the nipple 28N is disposed in an exposed or slightly extended relation within the upper end of the material passage 17M. The rear end of the nipple 28N has a tapered concentric seat 28S formed therein against which the valve member 28 may be seated. As will be evident in Fig. 1, the valve member 28 is generally ball-like in form and is made from a resilient material such as rubber. Axially of the valve 28, a mounting sleeve 28M is extended through the valve in an interlocked relation, a screw head 28H being formed in an exposed relation on the forward end of the sleeve 28M, and the sleeve 28M has a threaded axial bore extended into the rear end thereof so that the sleeve 28M may be threaded onto the threaded forward end of the stem 29.

Forwardly of the head 29H, the nozzle 20 is tapered inwardly as at 29T, so as to terminate in a reduced forward end which defines a reduced internal material discharge orifice 18D, and the head 29H and the tapered portion 29T are surrounded in spaced relation by the outer cap 15C of the nozzle structure 15. The cap 15C has a cylindrical rear portion 15R which extends into an annular groove 12G formed in the forward face 12F of the fitting concentric with the bore 50, and an outwardly extending annular flange 15F on the cylindrical portion 15R fits against the face 12F so as to define the relative location of the cap 15C on the fitting 12. The collar 16 is flanged over the forward face of the flange 15F and is threaded onto the forward

portion of the extension 12E. Forwardly of the cylindrical portion 15R, the cap 15C is tapered inwardly as at 15T so as to terminate in a tapered discharge nose 15N that is aligned with the inner discharge orifice 18D. The discharge nose 15N is spaced outwardly at its rear end from the forward end portion of the inner discharge passage 18D, and extends forwardly so that material drawn from the passage 18D will be mixed with the aspirating air while the air and the material move forwardly through the discharge nose 15N.

It will be noted that the rear end of the cylindrical portion 15R fills but a small portion of the cross sectional area of the groove 12G which therefore has sufficient effective area to serve as a distributing passage for pressure air received from the main air passage 26 of the body 10. Thus the fitting 12 has a pair of parallel bores 55 extended rearwardly from the upper portion of the groove 12G and positioned so that the rear ends of such bores 55 open through the face 12R and into the bore 38. In this connection it should be noted that the passage or bore 38 normally serves both as an air passage and as a mounting space for supplemental valve means for governing or adjusting the action of the wing jets in conventional paint spray guns, as described in my aforesaid co-pending application. In producing an emulsion gun under the present invention, such supplemental valve means are not required and the rear end of the passage 38 is therefore closed by a plug 51.

From the foregoing description it will be evident that the present invention materially simplifies and reduces the cost of producing emulsion spray guns; and that such emulsion guns as produced under this invention are simple in character and may be easily cleaned and kept in repair by the user.

Thus while I have illustrated and described the preferred embodiment of my invention, it is to be understood that this is capable of variation and modification and I therefore do not wish to be limited to the precise details set forth, but desire to avail myself of such changes and alterations as fall within the purview of the following claim.

I claim:

50. An emulsion spray head adapted for use with a spray gun body having a main control member, a main air valve in the gun body actuated by the control member, the gun body having an air passage therethrough, a mounting face on the gun body, the spray head having a complementary mounting face on one end adapted to be secured to the mounting face of the gun body, a nozzle receiving means on an opposite face of the spray head and a material inlet passage through the spray head extending downwardly therefrom between the two faces, the spray head having an air passage therein above the material passage and communicating with the main air passage of the gun, an air receiving and distributing circumferential groove in the nozzle receiving face in communication with and receiving air from the air passage in the spray head and adapted to distribute the air, an outer nozzle secured to the nozzle receiving face and having a rearwardly extending cylindrical portion spaced inwardly from an outer cylindrical wall thereof and forming a cylindrical shoulder on the nozzle adjacent the cylindrical portion, the cylindrical portion being of less cross sectional thickness than the width of the groove and of less length

than the depth of the groove when positioned therein, the cylindrical portion thereby serving to center the outer nozzle, the cylindrical shoulder abutting that part of the nozzle receiving face of the spray head outwardly of and surrounding the receiving and distributing groove, the outer nozzle having an interior cylindrical portion in communication with the circumferential receiving and distributing groove, an inner nozzle disposed within the outer nozzle and having a cylindrical portion thereof concentrically within and spaced from the cylindrical portion of the outer nozzle and forming therewith a cylindrical air receiving distributing passageway that is in direct communication with the circumferential groove, a mounting nipple engaging the nozzle receiving face of the spray head and extending laterally into the material inlet passage and providing a valve seat on the inner end thereof, a valve member comprising a valve rod slidably mounted in said head and movable by said main control member, a valve mounting

sleeve threadably mounted on the valve rod, a resilient ball-like valve member secured to said mounting sleeve and cooperating with said valve seat to prevent material flow from said material passage into the inner nozzle.
